UNITED STATES PATENT OFFICE.

JOHN E. SMITH, OF LAUREL, AND WILLIAM F. SULT, OF GILMAN, IOWA.

DESIGN FOR A HAT, CAP, OR SIMILAR ARTICLE.

43,908.

Specification for Design.

Patented Apr. 22, 1913.

Application filed April 11, 1912. Serial No. 690,178. Term of patent 7 years.

To all whom it may concern:

Be it known that we, JOHN E. SMITH and WILLIAM F. SULT, citizens of the United States, residing at Laurel and Gilman, respectively, in the county of Marshall and State of Iowa, have invented a new, original, and ornamental Design for Hats, Caps, or Similar Articles, of which the following is a specification, reference being had to the accompanying drawings, forming a part thereof, in which—

We claim:

The ornamental design for a hat, cap, or similar article, as shown.

JOHN E. SMITH.
WILLIAM F. SULT.
